UNITED STATES PATENT OFFICE.

JOHN W. HUDSON, OF WELLINGTON, ILLINOIS, ASSIGNOR OF ONE-HALF TO
HENRY W. NORTEN, OF SAME PLACE.

VICE.

SPECIFICATION forming part of Letters Patent No. 288,438, dated November 13, 1883.

Application filed October 10, 1883. (No model.)

To all whom it may concern:

Be it known that I, JOHN W. HUDSON, a citizen of the United States, residing at Wellington, in the county of Iroquois and State of Illinois, have invented certain new and useful Improvements in Vises; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to vises adapted for service on work-benches and the like; and the novelty consists in the construction, adaptation, and arrangement of parts, as will be more fully hereinafter set forth, and specifically 20 pointed out in the claims.

The object of my invention is to provide an adjustable vise which shall not only swivel, and thus be capable of having its jaws disposed at such angles with respect to the bench that all 25 shapes of work held by the vise may be securely held in such manner in relation to the workman as to be conveniently operated upon, but shall also have means for conveniently adjusting one jaw in relation to the other, so that the 30 jaws may embrace irregular forms. The invention also contemplates novel means for securing the vise to the bench.

The invention consists in mounting the main 35 leg of the vise pivotally in swivel-frames both above and below, which frames are connected with the bench; in pivotally mounting the shorter leg upon a shoulder of the main leg, so that it shall be capable of oscillating and being adjusted at desired locations at will, and in other 40 details of construction, which will be readily understood by referring to the accompanying drawings, which form a part of this specification, and in which—

Figure 1 is a side elevation of my improved 45 vise; Fig. 2, an elevation of the short leg thereof; Fig. 3, a top plan view of the swivel plate and frame which are wedged to the main leg, taken through the line $z-z$, Fig. 1; Fig. 4, a top 50 plan view of the bench-plate with the swivel-plate and wedge-frame in position, taken through the line $l-l$, Fig. 1; Fig. 5, a section of

the lower portion of the shorter leg and its means for adjustment and locking; Fig. 6, a detail view of the jaws arranged at an angle to each other; Fig. 7, a perspective view of 55 the locking-plate, and Fig. 8 a cross-section through the line $x-x$ of Fig. 1.

Referring to the drawings, in which similar letters of reference indicate like parts in all the figures, A designates the bench-top, and A' the standard thereof.

Secured upon the standard at b is a swivel-frame, B, in which is stepped the lower end of the main leg C.

Secured upon top of the bench is a frame, D, 65 in the lower arm, d, of which is a series of holes, d', arranged equidistant from the pivot α of the locking-plate E. These holes d' correspond in location with a similar series of holes, e', in the plate E, and the upper arm, d'', of the plate or frame D has two or more holes, d'', through which a pin may be inserted to lock the plate E in any desired location. The plate E has an arm, E', which extends outwardly from the bench, and it is embraced by a strap, F. This 70 strap F also embraces the upper portion of the leg C and the upper arm of the spring G, which serves to throw the jaws apart, and these parts—that is to say, the arm E' of the plate E, the leg C, and spring G—are held together by the 75 wedges g, g, without puncturing or otherwise weakening any of the parts. By this means of securing these said parts together they may readily be taken apart and replaced at will.

Formed with or rigidly secured to the leg C 85 is an arm or shoulder, H, in which is stepped the lower end of the short leg I. This leg I has a cylindrical portion, i, and a polygonal portion, i'. A locking-plate, J, having a polygonal aperture to correspond with the portion i' 90 of the leg I, is hung upon said leg above the arm H, and when this plate J is elevated until its central aperture is opposite the cylindrical portion i of the leg I the said leg may be oscillated upon its bearings. When, however, the 95 polygonal portions of each are engaged, the flanges j embrace three sides of the arm H, and the leg I is firmly locked in its desired adjustment.

The jaws g' of the spring G are polygonal, to 100 correspond with the form of the leg I where the spring-jaws impinge, and by this construction

the said spring bears from the outside and forces the leg I outward squarely, whatever may be its position in relation to the leg C. The clamping-jaw of the leg C is designated by the letter M, and that of the leg I by the letter N. The jaws are provided with the ordinary screw and socket; but in order to allow the free oscillation of the leg I, the hole I', through which the screw-arm passes, is elongated laterally, as shown in Fig. 2.

Modifications in details of construction may be made without departing from the principle or sacrificing the advantages of my invention, the essential features of which have been fully shown and explained.

Having thus described the invention, what I claim, and desire to secure by Letters Patent of the United States, is—

1. In an adjustable vise, and in combination 20 with the main leg C thereof, the swivel-frame B, frame D, locking-plate E, connections between the said plate and leg, and a locking-pin, as set forth.

2. The frame D, having arms *d d'*, perforated as shown, the locking-plate E, having perforations *e* and pivot *e*, the strap F, embracing the arm E', the wedges *g g*, combined with said leg C, and spring G, as and for the purposes set forth.

3. The leg I, having cylindrical portion *i*, polygonal portion *i'*, and elongated aperture I', combined with the shoulder or arm H and the locking-plate J, having flanges *j*, as and for the purposes set forth.

4. The combination of the leg C and the leg I, swiveled as shown, with the swivel-frame B, the frame D, as described, the locking-plate E, having perforations *e*, and arm E', the strap F, wedges *g g*, and spring G *g'*, all arranged and operating as set forth.

In testimony whereof I affix my signature in presence of two witnesses.

JOHN W. HUDSON.
